UNITED STATES PATENT OFFICE.

EDWIN L. BLABON, OF BRYN MAWR, PENNSYLVANIA, ASSIGNOR TO GEO. W. BLABON COMPANY, OF NICETOWN, PENNSYLVANIA, A CORPORATION OF PENNSYLVANIA.

LINOLEUM.

1,132,647.

Specification of Letters Patent. Patented Mar. 23, 1915.

Application filed October 2, 1914. Serial No. 894,596.

To all whom it may concern:

Be it known that I, EDWIN L. BLABON, a citizen of the United States, residing at Bryn Mawr, Montgomery county, Pennsylvania, have invented certain Improvements in Linoleum, of which the following is a specification.

This invention is designed primarily to provide an inexpensive, durable and superior linoleum floor covering that is not substantially affected by water or moisture.

In its preferred form, it comprises a felt backing fabric impregnated with asphaltum or a luminous product on which is mounted linoleum composition in any usual form and manner.

It will be understood that the impregnating material is fluid when hot and in such condition the felt backing can be impregnated or saturated to the desired degree by passing it through or leaving it for a sufficient time in a bath of such material in fluid condition. As such impregnated material in its solid condition is rendered adhesive by heat, this property facilitates and improves the adhesion of the linoleum composition to the backing.

The accompanying drawing is a perspective view of a form of my new product with a corner of the backing detached from the

linoleum composition for the purpose of illustrating the structure.

As represented in the drawing, the product comprises the felt backing A, impregnated with asphaltum, in combination with the linoleum composition body or face B, made in any usual manner, the backing and face or body adhering satisfactorily by reason of their inherent properties when heated and subjected to pressure.

Having described my invention, I claim:

1. The product comprising a body of linoleum composition in combination with a backing fabric of felt treated with a bituminous substance.

2. The product comprising a body of linoleum composition in combination with a backing fabric of felt impregnated with asphaltum.

3. The product comprising a body of linoleum composition in combination with a backing fabric of felt impregnated with asphaltum adhering to said composition.

In testimony whereof, I have hereunto set my name this 28th day of September, 1914, in the presence of the subscribing witnesses.

EDWIN L. BLABON.
